No. 836,320.

PATENTED NOV. 20, 1906.

P. J. HANLON.

PNEUMATIC BOBBIN CONVEYER FOR MILLS.

APPLICATION FILED MAY 2, 1906.

UNITED STATES PATENT OFFICE.

PATRICK J. HANLON, OF LEICESTER, MASSACHUSETTS.

PNEUMATIC BOBBIN-CONVEYER FOR MILLS.

No. 836,320.

Specification of Letters Patent.

Patented Nov. 20, 1906.

Application filed May 2, 1906. Serial No. 314,771.

To all whom it may concern:

Be it known that I, PATRICK J. HANLON, a citizen of the United States, residing at Leicester, in the county of Worcester and State of Massachusetts, have invented a new and useful Pneumatic Bobbin-Conveyer for Mills, of which the following is a specification.

My invention relates to a bobbin-conveyer adapted to receive bobbins from the several parts of one or more weaving-rooms and convey them without interference to the spindle-room or any other desired part of the mill.

The principal objects of my invention are to provide means whereby such a conveyer can be efficiently operated; to provide means whereby the bobbins can be dropped into the conveyer at as many points as may be convenient in the weaving room or rooms; to guard against any interference between one bobbin and another when a plurality attempts to enter any portion of the conveying-tubes at the same time; to provide an efficient construction for turns in the pipes whereby said turns can be reduced to a small radius; to provide means whereby the air may be brought into the conveyer from outside the building and discharged therefrom outside the building, thereby avoiding the drafts ordinarily encountered in conveyers of this character, which are extremely dangerous in case of fire; to provide an efficient means for discharging the bobbins from the conveyer without interfering with the passage of air therefrom, and to generally improve the construction and operation of conveyers of this character.

Reference is to be had to the accompanying drawings, which illustrate a preferred embodiment of my invention, and in which—

Figure 1 is a side elevation of a conveyer built according to my invention and showing one way in which it can be located in the mill. Fig. 2 is a side elevation of a portion of the conveyer, illustrating the manner of depositing the bobbins therein. Fig. 3 is an elevation of a short bend in the conveyer. Fig. 4 is a side elevation of the discharge device, and Fig. 5 is an end elevation of the same.

The pneumatic conveyers which have heretofore been designed for the purpose of carrying the so-called "cartridges" and other packings containing articles have been in general of a very simple construction, as these cartridges were especially designed for use in this manner, and consequently the problems involved were reduced to comparatively simple

terms by the especial design of the cartridges. When it is attempted, however, to convey bobbins the form of which is fixed, it is found that additional problems are encountered and that the pneumatic conveyers which served efficiently for carrying the cartridges are not sufficient.

It is the principal object of my invention to so improve the pneumatic conveyer that it will be adapted to carry bobbins from the several parts of a weaving-room, for example, to a spinning-room of a mill. It is to be understood, however, that while especially adapted for carrying bobbins the improvements which I have made are applicable to pneumatic conveyers in general and can be used not only for the ordinary cartridges but for conveying other articles which are not ordinarily carried in this manner.

For the purpose of overcoming certain of the difficulties mentioned above I have provided a conveyer-tube 10 of somewhat larger diameter than the head of a bobbin, but sufficiently small to prevent two bobbin-heads passing through at once.

For the purpose of introducing the bobbins into the conveying-tube I have provided a series of intakes comprising conductors 11. These conductors are connected at their upper ends to vertical tubes 12, having hoppers 13 distributed about the weaving-room in convenient places to receive the bobbins. The tubes 12 are of such size as to permit only one bobbin to descend at a time. The conductors 11, it will be noticed, are provided with connections entering the tubes 12 and fitting the lower ends of the same and with a slanting surface 14 extending under each of the tubes 12 from the rear thereof. This slanting surface is sufficient to throw out the head or other end of the bobbin as it comes down the tube 12 into the main tube 10, so that the bobbin will assume an inclined position and be ready to pass along into the tube 10 in parallelism therewith.

The conductor is elongated at its lower end sufficiently to permit the bobbin to lie at full length therein above the tube 10, so that if when a bobbin enters the conductor another bobbin is passing along the tube 10 the upper one will rest upon it and permit the lower bobbin to pass through the tube 10 without taking the upper one with it. The upper bobbin will then fall down into the tube and be carried along by the current of air which is furnished by means of a fan 15 or any other

convenient apparatus for this purpose. It will be seen that if two bobbin-heads, one above the other, reach the discharge end of the conductor 11, one of them resting on the bottom of the tube 10, the slanting surface of the conductor will engage one of the heads and hold it back until the other has passed along sufficiently to let the second bobbin fall into the tube 10.

10 The main tube preferably extends along the top of the room below the weaving-room just below the ceiling and is supplied with air, as has been stated, by a fan which receives its supply from a tube 16, extending through the wall of the building. The main conveyer-tube, passing, as it does, from the weaving-room to a spinning-room, which is usually on another floor, must be provided with bends to permit the bobbins to freely pass through it, changing direction as often as may be necessary. It is preferable, also, to have these bends as short as possible, and for this purpose I have provided an ordinary rounded surface 17 on the outside of each bend, forming a continuation of the two parts of the main tube which it connects. Instead of carrying a curved tube around the bend I have provided a flat surface 18 opposite the rounded surface 17, which, while guiding the bobbins, will not interfere with their turning in the bend and permits them, in fact, to turn at a very short angle. By the use of this improved bend or elbow the conveyance of the bobbins is secured with a reduction in friction and an increase in speed. The forward end of the bend acts also like the forward end of the conductor 12 to prevent two bobbin-heads leaving at once.

As was stated above, the air is taken into the conveyer through one of the outer walls of the building, and it is preferably discharged from it through the same or another wall. This operation is preferred on account of the fact that with the ordinary construction of pneumatic conveyer a powerful draft is furnished in case of fire, which greatly hampers the efforts of the fire department in controlling the flames.

In order to discharge the air through the wall of the building and intercept the bobbins in such a manner that they will remain within the building, I have provided a discharging device comprising a skeleton frame 19, flaring from the end of the conveyer-tube 55 and extending over the space between the end of this tube and a conical receiver 20. The lower side of the space between the tube and receiver is open to permit the bobbins to fall.

Inside the receiver 20 is a flexible screen 21, which is made of wire-cloth or any other material adapted to permit the passage of air and intercept solid articles. Behind the screen 21 is a nozzle 22, which preferably extends from the wall to discharge the air out-

side the building. If desired, this nozzle may be caused to return to the inlet 16, so that the air will be forced around the conveying-tube without passing to the outer air or receiving any additions from it. The same form of nozzle is used in both cases.

It will be seen that by the employment of the principles above set forth, whether in the form shown or otherwise within the scope of the claims, the pneumatic conveyer is amply adapted for the purpose of conveying bobbins in mills.

I am aware that many modifications may be made in the form of apparatus illustrated without departing from the scope of my invention as expressed in the claims. Therefore I do not wish to be limited to the particular construction shown; but

What I do claim, and desire to secure by Letters Patent, is—

1. In a pneumatic bobbin-conveyer for mills, the combination of a main conveying-tube, means for introducing air into one end of the tube under pressure, and an intake comprising a conductor having an elongated lower end opening into the upper side of the tube along the entire length of said lower end, a tube entering the upper end of the conductor, and means in the intake for deflecting the ends of articles introduced to make them enter the main tube parallel therewith.

2. In a pneumatic bobbin-carrier for mills, the combination of a main conveying-tube having a horizontal portion, means for forcing air along the tube under pressure, and an intake comprising a conductor having an elongated horizontal lower end opening into the upper side of the tube along the entire length of said lower end, and a vertical tube entering the upper end of the conductor, said conductor having a slanting surface located substantially entirely under said vertical tube.

3. In a pneumatic conveyer, the combination of a main conveying-tube having a substantially horizontal portion, and an intake therefor comprising a conductor having an elongated lower end opening into the tube along the entire length of said lower end, said length being equivalent to the length of the article to be carried, said conductor having a tube entering its upper end, a slanting surface descending from the lower end of the tube to the forward end of said opening, and a second surface extending from the other side of the lower end of the tube slanting in the direction toward the discharge end of the lower tube and located substantially entirely under said tube entering the upper end of the conductor.

4. A pneumatic conveyer having an intake comprising a substantially triangular conductor having one side lying along the main tube of the conveyer and another side located at an angle thereto and adapted to

receive articles dropped into the intake, said conductor constituting means for preventing two of the articles to be conveyed from passing into the main tube from said intake.

5 5. In a pneumatic conveyer, the combination of a main conveying-tube, an intake therefor having a tube entering it at one end and having an elongated opening at the other end entering the main tube, the walls of said intake slanting in a direction with the current of air, and a bend in said main tube, said bend having an outer curved surface and an inner flat surface.

15 6. In a pneumatic bobbin-conveyer for mills, the combination of a main conveying-tube, means for introducing air into the tube under pressure, and an intake comprising a conductor having an elongated lower end opening into the upper side of the tube along the entire length of said lower end, and a tube entering the upper end of the conductor, said main tube having a bend provided with a curved outer surface, and a flat inner surface, the outer surface being adapted to guide bobbins over the bend and the inner surface to prevent a plurality of bobbins passing to the bend of the main tube.

25 7. A pneumatic conveyer having a main tube, parts of said tube being at an angle to each other, and a bend located between said parts, said bend comprising a casing having a curved outer surface, and a flat inner surface extending across the corner formed by the two parts of the tube.

30 8. A pneumatic conveyer having a main tube, parts of said tube being at an angle to each other, and a bend located between said

parts, said bend comprising a casing having a curved outer surface and a flat inner surface extending across the corner formed by the two parts of the tube, and a discharge device comprising a receiver, and a skeleton frame between the receiver and the end of the main tube.

40 9. In a pneumatic conveyer, the combination of a main tube, a receiver, a skeleton frame between the main tube and receiver, and a partition in the receiver adapted to permit air to pass through it and to prevent the passage of the articles conveyed.

45 10. A discharge device for a pneumatic conveyer comprising a conical receiver, a skeleton frame for connecting said receiver with the main body of the conveyer, and a screen located in said receiver for permitting air to pass and intercepting articles conveyed.

55 11. A pneumatic bobbin-carrier for mills comprising a conveying-tube passing from the weave-room to the spinning-room, means for introducing outside air into the tube under pressure within the weave-room, means for discharging air from the tube into the outside air from the spinning-room and intercepting bobbins carried by the conveyer, and means located at a plurality of points for introducing bobbins into the conveyer in the weaving-room.

60 In testimony whereof I have hereunto set my hand in the presence of two subscribing witnesses.

PATRICK J. HANLON.
